(74) Attorney, Agent, or Firm — Richard L. Mikesell, Esq.

(57) CLAIM

The ornamental design for a T-shirt, as shown and described.

DESCRIPTION

FIG. 1 is a top, rear perspective view of a T-shirt with a visor in its stowed position showing my new design;
FIG. 2 is a left side elevational view thereof; the undisclosed right side elevational view being a mirror image thereof; and,
FIG. 3 is a front elevational view thereof; and,
FIG. 4 is a bottom plan view thereof, again showing the stowed visor.

1 Claim, 2 Drawing Sheets
